(57) **CLAIM**

We claim the ornamental design for a cervical cage, as shown and described.

DESCRIPTION

FIG. 1 is a front isometric view of a cervical cage; FIG. 2 is a left side elevation view of the cervical cage of FIG. 1;

FIG. 3 is a right side elevation view of the cervical cage of FIG. 1;

FIG. 4 is a front elevation view of the cervical cage of FIG. 1;

FIG. 5 is a rear elevation view of the cervical cage of FIG. 1;

FIG. 6 is a top plan view of the cervical cage of FIG. 1;

FIG. 7 is a bottom plan view of the cervical cage of FIG. 1;

FIG. 8 is a front isometric view of a cervical cage;

FIG. 9 is a left side elevation view of the cervical cage of FIG. 8;

FIG. 10 is a right side elevation view of the cervical cage of FIG. 8;

FIG. 11 is a front elevation view of the cervical cage of FIG. 8;

FIG. 12 is a rear elevation view of the cervical cage of FIG. 8;

FIG. 13 is a top plan view of cervical cage of FIG. 8; and, FIG. 14 is a bottom plan view of the cervical cage of FIG. 8.

The broken lines in FIGS. 1-14 indicate the bounds of the claimed design and form no part of the claimed design.
